UNITED STATES PATENT OFFICE.

JOSEPH ERRET, OF CLEVELAND, OHIO.

STAKE-SOCKET.

1,333,396.

Specification of Letters Patent. Patented Mar. 9, 1920.

Application filed April 17, 1919. Serial No. 290,727.

To all whom it may concern:

Be it known that I, JOSEPH ERRET, a citizen of the United States, residing at Cleveland, in the county of Cuyahoga and State 5 of Ohio, have invented a new and useful Improvement in Stake-Sockets, of which the following is a full, clear, and exact description, reference being had to the accompanying drawing, forming part of this specification, in which—

Figure 1 is a front elevation partly broken away showing a stake socket embodying my invention.

Fig. 2 is a section on the line II—II of Fig. 1.

Fig. 3 is a perspective view of the stake socket with the stake removed, and

Fig. 4 is a perspective view of the spring.

My invention has relation to certain new 20 and useful improvements in stake sockets for vehicle bodies. It has been customary heretofore to use a plain wooden stake with the lower end inserted in a pocket secured to the vehicle body. This construction is objectionable in that after the stakes are inserted, they frequently get wet and swell to such an extent that they cannot be removed without driving them up from the bottom. This frequently destroys the stake. The 25 stakes also very often break off above the stake pockets. With the present heavy trucks, such as motor driven trucks, which use large stakes and carry heavier loads, it is desirable to provide a stake socket which 30 will overcome these objectionable features. My invention does this in a simple and effective manner. It also provides a construction in which shorter wooden stakes may be employed, which is much stronger than the 35 ordinary wooden stake, and in which there may be a relatively loose fit between the stake socket and the stake pocket without rattling.

The nature of my invention will be best 40 understood by reference to the accompanying drawing, in which I have shown a preferred embodiment thereof and which will now be described, it being premised, however, that various changes can be made in 45 the details of construction, arrangement and combination of the parts without departing from the spirit and scope of my invention, as set forth in the appended claims.

In this drawing the numeral 2 designates

a stake pocket plate of the usual character 55 having therein the pocket 3.

4 designates my improved stake socket, formed of metal and having a cavity 5 into which the lower end portion of the wooden stake 6 is fitted and which is formed with 60 downwardly and inwardly tapering outer surfaces. The socket is provided with the upwardly extending straps 7 which can be made of any desired length, and which are secured by rivets 8, or other suitable attaching devices, to the stake. The upper edge portion of the socket 4 is preferably flanged outwardly, as indicated at 9, such flange forming a stop for engagement with the upper edge of the stake pocket 3. One or both 65 sides of the socket 4 is provided with an opening 10 through which may project the bent or bowed portion 11 of a spring 12 which is seated in the socket below the lower end of the stake 6. By forming an opening 70 10 in both faces of the socket, the spring may be inserted to either side and thus make the same socket readily adaptable to right or left use. The bowed portion 11 of the spring frictionally engages the inner wall 75 of the socket and thus prevents rattling and the stake jumping out, although permitting a loose fit between the socket and the pocket. Inasmuch as it is necessary for the wooden 80 stake to extend but a short distance downwardly into the socket, the stakes may be made much shorter than would otherwise be required. The straps 7 provide a strong 85 reinforce for the wooden stakes. Stakes provided with my improved sockets cannot 90 swell so as to become tight and may be readily removed at any time without injury.

It will be readily understood that my invention is not limited to the use of the particular form of spring which I have illustrated, since springs of various kinds may be employed. The spring may also act through a narrow face of the socket instead of through one of the wider faces as may be necessary in the case of sockets for narrow stakes, and various other changes may be made within the scope of the claims.

I claim:

1. A stake socket, comprising a socket portion having long strap members extending upwardly from opposite sides thereof, and adapted to form attaching means for the socket and reinforcing means for the

stake, said socket portion having an opening in one of its faces, and a spring seated in the socket and having a bowed portion projecting through said opening, substantially as described.

2. A stake socket having a cavity to receive the lower end of a stake, one wall of said cavity having an opening therein, and a U-shaped spring seated in said cavity and formed with a bowed portion which projects through said opening, substantially as described.

10 3. The combination with a stake pocket having a tapered cavity, of a stake socket

tapered externally to fit in the cavity of the 15 pocket, said socket having an upper portion to fit the lower end of a stake, and having an opening in one wall below said portion, and a spring seated in the socket below its stake-receiving portion and having a portion which projects through the said opening and frictionally contacts with the inner wall of the pocket cavity, substantially as described.

20 In testimony whereof, I have hereunto set 25 my hand.

JOSEPH ERRET.
